UNITED STATES PATENT OFFICE.

RUSSELL T. KINGSFORD, OF WYNCOTE, AND WILLIAM H. RICHTER, OF PHILADELPHIA, PENNSYLVANIA, ASSIGNEES TO ATWATER KENT MANUFACTURING COMPANY, OF PHILADELPHIA, PENNSYLVANIA, A CORPORATION OF PENNSYLVANIA.

TELEPHONE MAGNET SYSTEM.

Application filed July 2, 1925. Serial No. 41,031.

Our invention relates to the magnet system of telephonic apparatus for converting sound-representing current into sound, or vice versa, and particularly to magnet systems for amplifying telephones, loud speakers, radio speakers or the like, utilized in connection with radio receiving apparatus.

In accordance with our invention, the magnetic system comprises a field yoke or frame, preferably permanently magnetized, having pole pieces whose pole faces are accurately trued or determined, procured by grinding or equivalent operation, and which are in substantially the same plane, in combination with a relatively stiff or rigid vibratile armature member or reed having at its opposite ends similar accurately trued or determined faces, one of which at the free end of the armature member is spaced from the trued surfaces of the pole pieces, and the other of which at the other end of the armature member is secured against an accurately trued or ground surface on the yoke or magnet frame itself, or, and preferably, an accurately trued or ground surface of a member rigidly secured to the magnet frame or yoke and serving to space the fixed end of the armature member from the yoke or frame.

Further in accordance with our invention, the yoke or magnet frame has a bridging member, preferably integral therewith, extending transversely of the longitudinal alignment of the pole pieces, adjacent their ends, and displaced laterally from the plane of the yoke or field frame and serving as a support or abutment for an adjusting screw or equivalent, of non-magnetic material, engaging the pole pieces and serving nicely to adjust the air gap between them and the free end of the vibratile armature member; and more particularly, the bridging member is of a width serving to hold or confine the magnet coils or windings.

Further in accordance with our invention, the greater energy available for movement of the telephone diaphragm, resulting from our construction, enables the ratio of amplitude of vibration of the vibratile armature member to the amplitude of vibration of the diaphragm to be substantially unity, even when the diaphragm is conical and of relatively large diameter.

Our invention is further characterized by a method of operating upon and assembling

the component parts of the magnet system, as hereinafter described.

Our invention resides in a magnet system and the method of production thereof as hereinabove described and claimed.

For an illustration of our apparatus, reference is to be had to the accompanying drawings, in which:

Fig. 1 is a vertical sectional view, partly in elevation, of apparatus embodying our invention.

Fig. 2 is a front elevational view of the magnet system.

Fig. 3 is a front elevation of the magnet yoke or frame with attached armature support.

Fig. 4 is a horizontal sectional view, on enlarged scale, partly in plan, taken on the line 4-4 of Fig. 2.

Fig. 5 is a vertical sectional view, on enlarged scale, partly in elevation, taken on the line 5-5 of Fig. 2.

The magnet system, its mounting and the mounting of the conical diaphragm, are of the general character disclosed and claimed in prior application Serial No. 32,875, filed May 26, 1925.

Referring to the drawings, 1 is a base or stand to which is secured by screw 2 a bracket member 3, to which is secured the upwardly extending arm 4, terminating in the supporting member 4, to which is secured by screws 5 the substantially rectangular frame or yoke 6 of the magnet system, suitable spacing members 7 intervening between the frame or yoke 6 and the support 4 through holes in which the screws 5 extend and have applied thereto on the rear of the support 4 the nuts 8.

Secured to the frame or yoke 6 by the same screws 5 are the inwardly extending pole pieces 9, in alignment with each other, and between whose inner ends is left an air gap. The pole pieces 9 may be of any suitable material, but preferably of Swedish iron or silicon steel. Surrounding the pole pieces 9 are the windings or coils C traversed by the voice- or sound-representing current, such as exists, for example, in the anode circuit of a detector or audio frequency thermionic amplifier as commonly utilized in radio receiving circuits. As usual, the two windings C operate cumulatively with each other to simultaneously strengthen or weaken the magnetic field acting upon the vibratile armature mem-

ber 10, of suitable material, and preferably of silicon steel whose hysteresis and eddy current losses are relatively low.

The yoke 6 is preferably permanently magnetized, and is preferably composed of chrome or tungsten magnet steel. It has poles of opposite signs at opposite ends thereof adjacent the points of attachment thereto of the pole pieces 9, 9, whereby at the inner 5 and adjacent ends of the pole pieces 9 are exhibited opposing north and south magnetic poles.

Substantially mid-way between the ends of the yoke or frame 6 there is a hole 11 therein, 15 in which is riveted the hollow or tubular shank 12 integral with the spacer member 13, of any suitable material, such as iron or steel, into which is threaded the screw 14 extending through a hole in the vibratile member 10 to 20 rigidly secure it to the member 13 and therethrough to the yoke or frame 6. The member 13 serves also as an abutment for the stiff reed or armature 11 about which it may flex or bend under the influence of the sound- 25 representing current.

Integral with the yoke 6 is the bridging member 15, offset from the plane of the yoke 6 on that side thereof opposite the armature 10. Member 15 is of greater width than the armature 10, and preferably of such width that it 30 confines the coils C, C between itself and the sides of the yoke 6, whereby the sides of the yoke 6 and the member 15 serve as abutments preventing substantial longitudinal movement 35 of the coils C upon the pole pieces 9.

The bridging member 15 serves also to support the adjusting screw 16, preferably of brass or non-magnetic material, threaded therethrough and having a flat end engaging 40 the adjacent ends of the pole pieces 9, 9, and bridging the gap between them. Adjustment of the screw 16 serves to flex the inner ends of the pole pieces 9, 9 toward the adjacent face 45 of the free end of the vibratile armature 10 nicely to adjust the effective air gap between them. Once the screw 16 is adjusted, it is locked by the nut 17.

Threaded into the vibratile member 10 is the pin or rod 18, to which is fixedly secured 50 the air-vibrating member as the conical diaphragm or tympan 19, of relatively large diameter, preferably upwards of six inches. The diaphragm has at its center the sheet metal conical structure 20 to which the dia- 55 phragm proper is secured, and the member 20 is provided with a sleeve 21 through which is threaded the screw 22 engaging the rod 18.

The diaphragm is supported solely by the magnet system, and particularly by the vibratile armature 10 thereof. The pin 18 may be attached to any suitable point along the armature 10, and preferably at such point thereon that the ratio of amplitude of vibration of the cone 19 to the amplitude of vibration 65 of the armature 10 at that part thereof

about the middle of the width of the pole pieces 9 is substantially unity. As indicated, the rod 18 may be attached to the armature 10 at the middle of the width of the pole pieces 9, though it will be understood that its position may be nearer or more remote from the fixed end of the member 10, and in those cases also the aforesaid ratio may vary slightly from unity.

The cone 19 at its periphery is free and 75 unconfined. To shield or guard the cone 19, which may be constituted of paper or thin sheet metal, there may be provided the housing or guard structure 23, Fig. 1, extending 80 around the periphery of the cone 19, and extending also to either or both sides thereof, but substantially spaced therefrom to permit free vibration of the cone throughout and at its periphery. The shield or housing structure 23 may be of sheet metal carried by or 85 integral with the several arms 4a.

The yoke 6 may be punched or stamped from sheet material of desired thickness, and the bridging member 15 offset from the plane 90 thereof by operation thereon by punch or die structure. Thereafter the member 6 is hardened preparatory to its permanent magnetization.

We have found that the operating characteristics of the magnet system herein described are materially improved by recourse 95 to refinements which, so far as we are aware, are novel in a system of the character described.

Spacer or abutment member 13 is riveted or 100 secured to the yoke 6, and thereafter the face a thereof adjacent the armature 10 is trued, as by grinding or equivalent operation, to effect a smooth true surface preferably substantially parallel to the plane of the yoke 6. 105 Preferably, however, this grinding of the face of member 13 is accomplished at the same time the faces of the poles 9 are ground, as hereinafter described.

The coils C, C are placed in their respective 110 openings o between the bridging member 15 and the sides of the yoke 6, the pole pieces then slipped through their open centers, and the screws 5 placed in position and the nuts 7 applied securely to hold the pole pieces 9 at 115 their outer ends against the sides of the yoke 6, with the two pole pieces in substantial alignment with each other. With the pole pieces so in their operative position upon the yoke 6, their inner ends are ground or similarly operated upon on their faces b presented to the armature 10, to true those faces and bring them substantially into the same plane. During this grinding or equivalent operation 120 it is preferred that the ends of the pole pieces 9 be slightly flexed outwardly by adjustment of the screw 16 toward the right, Fig. 5. The face of the abutment 13 is preferably ground at the time the pole pieces 9 are ground, thereby requiring but a single clamping of the 125 130

member 6 and attached parts in the grinding machine.

With the pole pieces 9 and coils C in place, and either before or after the grinding of the pole pieces, the hardened steel yoke 6 is magnetized, and thereafter preferably artificially aged.

The vibratile armature member 10 is similarly ground or operated upon at both ends, at its surfaces *c* and *d*, on its side adjacent the yoke 6 and pole pieces 9. It is thereupon placed in position upon the member 13 with its ground surface *c* in contact with the outer ground surface *a* of the member 13, and there rigidly secured by the screw 14. The ground face *d* at the free end of the armature 10 is accordingly disposed opposite the ground faces *b* of the inner ends of the pole pieces 9, defining therewith an accurately determined air gap whose length is thereafter adjusted, if necessary, by further adjustment of the screw 16 either to relieve the previous tension placed upon the pole pieces during the grinding operation, or to press them further toward the free end of the vibratile member 10. The air gap between the surface *d* of the member 10 and the surfaces *b* of the pole pieces 9 is very short, and materially shorter than the gap between the adjacent ends of the pole pieces 9. This air gap is of substantially equal length throughout, due to the grinding of the surfaces of the pole pieces and of the free end of the armature. And parallelism between the ground faces *d* and *b* is the more readily obtainable by grinding the surface *a* of the member 13 to parallelism with the ground surfaces *b* of the pole pieces. With the surface *a* ground accurately parallel with the ground surfaces *b*, and with the surfaces *c* and *d* on the armature 10 ground parallel to each other, the surfaces *d* and *b* are quite accurately parallel to each other and effect an air gap of uniform length, from which results a more uniform and more intense magnetic field in the short air gap, other things being the same; and with a relatively stronger magnetic field or more powerful action upon the armature 10 the latter may be relatively thicker, and therefore less easily flexed, and therefore partaking of smaller amplitude of vibration, substantially equal to the amplitude of vibration suitable for a large cone diaphragm, and this relation makes more readily obtainable the substantially unity ratio of amplitude of vibration of the conical diaphragm to the amplitude of vibration of the vibratile member 10 at its region approximate the middle of the width of the pole pieces 9.

While a spacer member 13 is utilized, with its surface *a* ground parallel to the faces *b* of the pole pieces, it will be understood that the member 13 may be riveted, secured to or integral with the armature 10, in which event the surface of the magnet frame 6 en-

gaged by the member 13 will be ground parallel to the faces *b* of the pole pieces, as well as the face of the member 13 engaging such ground surface of the magnet frame 6.

It will further be understood that a spacer member may be omitted and the end of the armature 10 secured directly against the yoke 6 with their engaging surfaces ground parallel to the faces *b* and *d* of the pole pieces and armature member, respectively.

What we claim is:

1. A telephone magnet system comprising a magnet frame, pole piece structure secured thereto at its one end and having at its other end a ground pole face, a vibratile armature bar secured adjacent its one end to said magnet frame and having its free end disposed adjacent and substantially parallel to said ground pole face, and a diaphragm of large area having small amplitude of vibration in unconfined air actuated by said vibratile armature bar.

2. A telephone magnet system comprising a magnet frame, pole piece structure secured thereto at its one end and having at its other end a ground pole face, a vibratile armature bar secured adjacent its one end to said magnet frame and having at its free end a ground face disposed adjacent and substantially parallel to said ground pole face, and a diaphragm of large area having small amplitude of vibration in unconfined air actuated by said vibratile armature bar.

3. A telephone magnet system comprising a magnet frame, pole piece structure secured thereto at its one end and having at its other end a ground pole face, a vibratile armature bar secured adjacent its one end to said magnet frame at a face ground parallel with said ground pole face, said armature bar having its free end spaced from and disposed parallel with said ground pole face, and a diaphragm of large area having small amplitude of vibration in unconfined air actuated by said vibratile armature bar.

4. A telephone magnet system comprising a magnet frame, pole piece structure secured thereto at its one end and having at its other end a ground pole face, a vibratile armature bar secured adjacent its one end to said magnet frame at a face ground parallel with said ground pole face, said armature bar having at its free end a ground face parallel with the face at its attachment to said magnet frame, and a diaphragm of large area having small amplitude of vibration in unconfined air actuated by said vibratile armature bar.

5. A telephone magnet system comprising a magnet frame, pole piece structure secured thereto at its one end and having at its other end a ground pole face, a vibratile armature bar secured adjacent its one end to said magnet frame and having at its free end a ground face disposed adjacent and substantially parallel to said ground pole face, said at-

tachment of said armature bar to said magnet frame comprising contacting ground faces parallel to the ground faces on the free end of said armature and said pole piece structure, and a diaphragm of large area having small amplitude of vibration in unconfined air actuated by said vibratile armature bar.

6. A telephone magnet system comprising a magnet frame, pole pieces therefor extending from opposite ends of said frame and having their inner ends spaced from each other, a vibratile armature bar secured adjacent its one end to said magnet frame and having its free end disposed adjacent the inner ends of said pole pieces and bridging the gap between them, said magnet frame having a member integral therewith extending transversely to said pole pieces and spaced therefrom, and a member carried by said last named member and adjustable with respect thereto engaging said pole pieces to adjust the gap between them and the free end of said armature bar.

7. A telephone magnet system comprising a circumferentially closed magnet frame, pole pieces therefor extending from opposite sides of said frame and having their inner ends spaced from each other, a vibratile armature bar co-acting with said pole pieces, said magnet frame having a bridging member integral therewith and extending transversely of said pole pieces, and a member carried by and adjustable with respect to said bridging member engaging said pole pieces for adjusting them with respect to said armature bar.

8. A telephone magnet system comprising a circumferentially closed magnet frame, pole pieces therefore extending from opposite sides of said frame and having their inner ends spaced from each other, a vibratile armature bar co-acting with said pole pieces, said magnet frame having a bridging member integral therewith and extending transversely of said pole pieces and offset from the plane of said frame, and a member carried by and adjustable with respect to said bridging member engaging said pole pieces for adjusting them with respect to said armature bar.

9. A telephone magnet system comprising a magnet frame, pole piece structure therefor extending inwardly from one side of said frame, a member integral with said magnet frame extending transversely of said pole piece structure, and a magnet winding on said pole piece structure confined between said member and said side of said frame.

10. A telephone magnet system comprising a circumferentially closed magnet frame, pole pieces extending toward each other from opposite sides of said magnet frame, magnet coils on said pole pieces, and a bridging member integral with said magnet frame extending transversely of said pole pieces and

confining said coils between it and said sides of said frame.

11. A telephone magnet system comprising a magnet frame, pole piece structure therefor, a co-acting vibratile armature bar whose free end co-acts with said pole piece structure, and means for securing said armature bar adjacent its one end to said magnet frame, comprising a member riveted to one of them, and an attaching member securing the other of them to said riveted member.

12. A telephone magnet system comprising a magnet frame, pole pieces therefor extending from opposite sides of said frame, said frame having a hole intermediate its said sides, a member having a hollow shank riveted in said hole, and a vibratile armature bar secured at its one end to said member and having its free end disposed adjacent the ends of said pole pieces.

13. A telephone magnet system comprising a magnet frame, pole pieces therefor extending from opposite sides of said frame, said frame having a hole intermediate its said sides, a member having a hollow shank riveted in said hole, and a vibratile armature bar secured at its one end to said member and having its free end disposed adjacent the ends of said pole pieces, said armature bar and riveted member engaging each other at parallel ground faces, said armature bar and said pole pieces having their adjacent faces ground parallel with said first named ground faces.

14. A telephone magnet system comprising a magnet frame, pole piece structure therefor, a co-acting vibratile armature bar whose free end co-acts with said pole piece structure, and means for securing said armature bar adjacent its one end to said magnet frame comprising a member riveted to one of them, and an attaching member securing the other of them to said riveted member, said riveted member and armature bar engaging each other at parallel ground faces, the adjacent faces of said pole piece structure and of the free end of said armature bar ground parallel to said first named ground faces.

15. In the production of a telephone magnet system, the method which comprises securing a pole piece at its one end to a magnet frame, grinding a face on said pole piece, grinding a face on said magnet frame parallel with the ground face on said pole piece, grinding parallel faces at the ends of an armature member, and securing said armature member at its one end with its ground face thereat in engagement with the ground face on said magnet frame to position the ground face at the free end of said armature member adjacent to and parallel with the ground face on said pole piece.

16. In the production of a telephone magnet system, the method which comprises securing a pole piece at its one end to a

magnet frame, slightly deflecting the free end of said pole piece, grinding a face on said free end of said pole piece while deflected, grinding a face on said magnet frame parallel with the ground face on said pole piece, grinding parallel faces at the ends of an armature member, and securing said armature member at its one end with its ground face thereat in engagement with the ground face 10 on said magnet frame to position the ground face at the free end of said armature member adjacent to and parallel with the ground face on said pole piece.

17. A telephone magnet system comprising

a magnet frame, pole pieces therefor extending from opposite sides of said frame and having their inner ends spaced from each other, a vibratile armature bar co-acting with said pole pieces, said magnet frame having a member integral therewith and extending 15 transversely of said pole pieces, and a member carried by and adjustable with respect to said magnet frame member engaging said pole pieces for adjusting them with respect to said armature bar.
